UNITED STATES PATENT OFFICE.

GAETANO MILONE, OF MIDDLETOWN, CONNECTICUT.

PADLOCK.

1,359,415.

Specification of Letters Patent. Patented Nov. 16, 1920.

Application filed April 19, 1920. Serial No. 375,004.

To all whom it may concern:

Be it known that I, GAETANO MILONE, a subject of the King of Italy, residing at Middletown, in the county of Middlesex and 5 State of Connecticut, have invented certain new and useful Improvements in Padlocks, of which the following is a specification.

My invention relates to improvements in padlocks, and the object of my improvement 10 is to produce a padlock that is safe and reliable in use, in that it by reason of its peculiar construction is relatively difficult to be opened accidentally or intentionally by unauthorized persons, and that at the same 15 time is of relatively simple construction, so as to be economical to manufacture.

In the accompanying drawing:—

Figure 1 is a front elevation of my improved padlock.

20 Fig. 2 is a rear elevation of the same.

Fig. 3 is a side elevation of the key.

Fig. 4 is an end elevation of the same.

15 Fig. 5 is a front elevation with the cover to the casing removed.

Fig. 6 is a front elevation of the body portion of the casing.

25 Fig. 7 is a sectional view on the line 7—7 of Fig. 6.

Fig. 8 is a front elevation, in part broken 30 away, with the key in position and the parts in the retracted position.

Fig. 9 is a front elevation of the cover plate, with the key-hole plate removed.

Fig. 10 is a side elevation of the cover 35 structure, with the key-hole plate in the open position.

My improved padlock comprises a lock body or lock proper 10 that is provided with a bow or shackle 11, one end 12 of the said 40 shackle being pivotally connected to the said body by means of a pivotal pin 13 and the other end 14 thereof being provided with a tongue 15 that is adapted to project inwardly through an opening 16 in the top 45 wall of the body 10 into the interior of the said body 10 where it is secured by suitable locking mechanism to be described.

The lock body 10 comprises the said mechanism, housed generally in a casing that is 50 composed of a casing body 17 and a cover 18.

The said casing body 17 comprises a shell-like structure having a back-plate 19 and a border wall supported thereby, the said border wall being designated generally by the character 20. The border wall 20 is interrupted at the top on one side as shown at 55 21 to provide an opening for housing the pivotal end 12 of the shackle 11, already mentioned, and on the other side has the opening 16, already mentioned, for admitting the tongue 15 on the locking end 14 of the said shackle 11.

The cover 18 comprises generally a plate-like structure that fits against the border wall 20 and is held in place by a plurality 60 of rivets 22.

On each of the two faces is a vertically directed structure of special character as follows:—On the rear face, slidably mounted on the back-plate 19 for vertical movement, is the plate 23 that serves as the release plate or tripping plate for releasing the key-hole plate 24 that is hinged to the front cover 18. The guide means for the said sliding release plate 23 comprises at the 70 upper end portion a pin 25 that is secured to the back-plate 19, extends through a slot 26 in the sliding plate 23, and has a head 27 on the end at the rear that is in bearing engagement with the rear face of the said 75 sliding plate 23. The head 27 is of vertically elongated form, suitably to cover the slot 26.

The casing is provided with a vertically directed slot 28 through which projects a 85 pin 29 that is mounted on the lower end portion of the vertically sliding release plate 23, the said pin 29 extending forwardly within the interior of the said casing substantially across the interior space. 90

The sliding plate 23 is normally positioned in the upper position, as limited by the slots mentioned, and is moved downwardly to release the key-hole plate 24 in opposition to a positioning spring 30. 95

The said spring 30 is made of sheet spring material, is secured to the side wall 20 in any proper manner by one end, as by means of the lower casing rivet 22, and extends generally horizontally across the lower por- 100

- tion of the interior space of the casing, the free end portion 31 bearing upwardly against the pin 29, the body portion 32, intermediate the said ends, being adjacent the middle of 5 the lock structure and accessible for being engaged by the catch 33 that is provided on the key-hole plate 24. The spring 30 serves as the keeper for the said catch 33 and holds the same normally in the locked 10 position, and is released by sliding the sliding plate downwardly, through the medium of the pin 29 that is engaged with the free end portion 31 of the said spring 32, as described.
- 15 Thus, as described, the pin 29 serves as guide means for the slide plate 23 and also as the releasing means for releasing the key-hole plate 24.

The catch 33 is adapted to slide into engagement with the upper face of the body portion 32 of the spring 30 and is provided on the lower face, that is opposed to the spring 30, with a notch 34 that fits and is adapted to receive the said opposed body 20 portion 32 for locking the key-hole plate 24 in the closed position.

The key-hole plate 24 is an elongated plate that is operatively mounted on the cover 18, is housed between two side strips 35 that are 30 fixed to the front face of the said cover 18, and is hinged by its upper end to the said side strips 35 by means of a pivotal pin 36 so as to be adapted to swing toward and away from the said cover 18. The catch 33 is 35 mounted on the rear face of the key-hole plate 24 and also mounted on the said rear face is a spring 37 that engages with the opposed front face of the cover 18 and that serves to force the key-hole plate 24 outwardly from the housing space between the side strips 35 when the catch 33 is released 40 from its engagement with the spring 30.

The key-hole plate 24 normally covers the key-hole 38 that is provided in the cover 18 45 for admitting the bit end 39 of the key 40.

The key post 41 for the key is provided in the form of a projection mounted on the back-plate 19 and fits a hole 42 in the end 43 of the key 40 and the bit portion 39 extends radially from the said end or hub portion 39 suitably for engaging with the bolt member 44 by a clockwise movement.

The engagement with the bolt member 44 is effected through the medium of a lug 45 55 that is in the path of the bit portion 39 and that extends downwardly from the body portion 46 of the said bolt member 44.

The bolt member 44 is positioned generally transversely of the lock body 10, 60 though actually, as shown, being slightly inclined for convenience in effecting engagement with the shackle 11, is operatively supported for sliding back and forth in the transverse direction for a limited movement, 65 is normally projected toward the left by

means of the bolt spring 47 that engages with the right end portion 48 of the body portion 46.

The lug 45 extends downwardly from the body portion 46 and extending generally 70 transversely or outwardly from the left end of the body portion 46 is the bolt 49 that is adapted to engage with the tongue 15.

As shown, the bolt 49 engages with the tongue 15 by means of a hole 50 therein, 75 through which the bolt is entered.

For guiding the bolt member 44 in such transverse movement the body portion 46 is provided with a slot 51 that is in engagement with cooperating means on the casing body 17 in the form of two fixed pins 52 that are positioned in proper relation for effecting such guiding.

The extreme lower right hand corner 53 of the key bit 39 contacts with the lower 85 guide pin 29 of the sliding plate 23 when the bit 39 is in registration with the key-hole 38 and serves as a guide in entering and withdrawing the key and prevents turning the key the wrong way for opening the lock 90 when the sliding plate 23 is in the normal uppermost position. When the sliding plate is lowered from the normal uppermost position the pin 29 is below the path of the key, which can then be turned in the counter-clockwise direction for engagement with the rear or right side of the lug 45 on the bolt member 44. Such movement of the key may be desired for relieving or cooperating with the bolt member spring 47 in throwing the 100 bolt.

The said bolt member spring 47 is made of spring strip sheet material, bent into approximately V-shape so as to have two arms, one engaging with the bolt member 44 and the other against one of the casing rivets 22, the middle portion being formed into an eye 54 for being mounted on a supporting pin 55 that is provided on the casing body 17.

As described, the key-hole, which is provided in the front face, is covered and protected by a key-hole plate that is mounted on the front plate or front face, and the said key-hole plate is locked in such protecting position by means of a cooperating locking device that is released by a plate that is 110 slidably mounted on the back plate or back face.

Also, the internal locking mechanism is such as to effect a safe and reliable locking 120 of the parts.

I claim as my invention:—

1. A padlock having a casing that is provided with a plate-like front wall and a plate-like back wall and having a keyhole opening in the said front wall, a keyhole guard plate hinged to the said front wall and having a catch pin on the rear face for being projected into the interior of the casing, a transversely directed spring mem- 130

ber positioned within the casing, supported by one end, and arranged to engage with the said catch pin, a release pin extended into the said casing and having contact engagement with the said spring, guide means for the said release pin in the form of a slot that is provided in the said back wall of the casing, a back slide plate mounted on the said back wall for longitudinal sliding

movement, and the said back slide plate 10 serving as the support for operatively supporting the said release pin.

2. A padlock as described in claim 1, the said release pin being positioned so as to serve as guide means for the key when admitted to the lock for operating the lock mechanism. 15

GAETANO MILONE.
